PRIME MOVER CONTROL SYSTEM

Joseph J. Ring and Beverly R. Nichols, Wauwatosa, Wis., assignors to Allis-Chalmers Manufacturing Company, Milwaukee, Wis., a corporation of Delaware

Application April 25, 1938, Serial No. 203,986

27 Claims. (Cl. 253—143)

This invention relates generally to prime mover control systems and particularly to systems controlling a prime mover of the type having adjustable runner vanes.

5 A control system for a prime mover should be accurately and quickly responsive to any condition tending to cause a change in the prime mover speed. Response to such speed changes should, however, follow a predetermined rate dependent 10 on the characteristics of the machine being governed. Thus it is frequently desirable to open the operating fluid control gate slowly and intermittently or to provide for a different rate of speed movement under different conditions. The 15 degree to which the gate is opened under different conditions should also be controllable to limit the power output or the load on the machine. Load or power limitation is normally employed during both the starting and the normal 20 operation of the machine to avoid excessive gate opening which would hinder initial synchronization of the governed machine, with other machines or which would allow the governed machine to tend to supply an excessive portion of 25 the total load. If an excessive load is taken by one machine, the machine will operate outside its normal range and will be unstable. To secure adequate and stable regulation of a machine subject to varying load, the control system must 30 be provided with means by which a predetermined speed drop or droop is permitted when the load on the unit changes.

Modern machines are frequently to be operated at remote points and without the constant supervision of an attendant in the station itself. It is accordingly necessary to provide a governing system with means by which abnormal operating conditions or failure of the governing mechanism itself will operate to shut down the machine. 35 When such shutdown occurs, it is desirable that the usual supply of oil pressure to the control system is interrupted to make the control system ineffective until the entire control system has again been placed in the proper operating 40 condition. When the prime mover governed is a turbine with adjustable runner vanes, it is very necessary to adjust the vanes to a steep angle to obtain the maximum torque during starting and to make such adjustment automatically. The 45 control system should therefore provide for setting the runner vanes to a steep angle prior to starting and such setting should be relinquished to the normal vane control mechanism at least as soon as the machine is at its full load operating speed.

It is therefore an object of the present invention to provide a control system for a prime mover in which system the rate of movement of the gate controlling the flow of operating fluid to the prime mover follows a predetermined plan 5 regardless of the operation of other portions of the system tending to cause the gate to move at a different rate.

Another object of the invention is to provide a prime mover control system in which the gate 10 controlling the flow of operating fluid to the prime mover is opened during starting to a predetermined position corresponding substantially to normal speed at no load and is subsequently permitted to open farther under the control of 15 a speed governor.

Another object of the invention is to provide a prime mover control system which will secure stable predetermined operation of the prime mover at all loads from no load to full load and will 20 allow only a predetermined speed droop to take place over the entire load variations.

Another object of the invention is to provide a prime mover control system which will interrupt 25 operation of the prime mover upon the occurrence of abnormal prime mover operating condition or upon the failure of the control system itself.

Another object of the invention is to provide a control system for prime mover generating units in which fluid pressure supplying the operating cylinders in the control system is either 30 manually or automatically interrupted to cause a shutdown of the prime mover followed by closure of a blocking valve to prevent redistribution of operating fluid to the control system.

Another object of the invention is to provide a control system for a prime mover having adjustable runner vanes in which the runner vanes are automatically caused to assume steep angular 35 position prior to starting of the prime mover to increase the starting torque thereof and are automatically returned to normal position after the starting operation is completed.

Objects and advantages other than those above set forth will be apparent from the following description when read in connection with the accompanying drawing in which:

Fig. 1 diagrammatically illustrates a hydraulic turbine driven generator unit having applied thereto an automatic speed control system embodying the various elements of the present invention and,

Fig. 2 diagrammatically illustrates, in side view, the structure of the runner vane control portion of the control system, which is particularly adapt- 55

ed for adjustment to produce steep tilt position of the runner vanes upon starting.

The various elements constituting the control or governing system are not shown in their relative positions, their true size nor in their relative proportions but are shown diagrammatically to more clearly facilitate explanation of the construction and operation of the system.

Referring to the drawing by characters of reference, the control system is shown as applied to a prime move such as a hydraulic turbine designated at 10 and shown as being of the adjustable propeller type driving an alternating current generator 11 connectible with and disconnectible from the usual power line by conventional switch gear means well known in the art and therefore not shown. The turbine 10 comprises a casing 12 which forms a peripheral water inlet in which are mounted a series of movable vanes forming a gate 13. The term "gate" is intended to include means other than those disclosed and which may be used for the purpose of controlling and guiding the flow of pressure fluid to any prime mover to which a governing system embodying any of the elements herein shown, is applied. The gate vanes are mounted on stems 14 journaled at the top and bottom in portions of the casing 12. The upper stem portions extend through the upper portion of the casing to provide for attachment of a conventional linkage connection with a shifting ring 16 which is adapted to be shifted into different positions and to control the position of the gate vanes and hence to control the flow of fluid to the turbine. The shifting ring 16 is connected with and actuated by the piston 17 of a fluid pressure operated servomotor 18.

The turbine 10 is connected with generator 11 by a hollow shaft 19 which is supported against movement at angles to its axis by a bearing 21 and on which is mounted the turbine runner comprising a hub 15 from which extend, substantially radially, a series of vanes 22 journaled in suitable bearings in the hub. The inner ends of the vanes 22 are severally provided with trunnions 23 and 24 are connected by linkage mechanisms 24 with a cross head 26 which is guided to be reciprocated axially of the shaft by an operating rod 27. It will be understood that the relative positions of the runner vanes govern the area of the fluid flow passages or openings between the vanes and that adjustment of the runner vanes increases or decreases the area of the flow passages depending upon the direction of the movement of the vanes. The cross head 26 is fixed to the lower end of the operating rod 27 which extends upwardly through the runner shaft 19 and is fixed to the piston 28 of a fluid pressure operated servomotor 29 which is mounted in or is formed as a portion of the runner shaft preferably adjacent to the point where the runner shaft is joined to the hollow generator shaft 31. The servomotor piston 28 is double acting and two tubes 32 and 33 are arranged in telescopic relation within the generator shaft for the purpose of supplying fluid pressure to the two sides of the piston to operate the same in either direction. The outer tube 32 supplies fluid for the downward movement of the piston 28 and connects with the lower chamber of a distributing head 34 secured to the top of the generator frame. The tube 32 extends downwardly through the hollow bore of the generator shaft 31 and is sealed against the escape of fluid pressure therefrom. The inner tube 33 supplies fluid pressure for the upward movement of the piston 28 and is fixed thereto and rotates with the shaft 31.

The tube 33 communicates with an inclined passage 36 through the piston 28 and is provided with perforated openings 37 in the tube portion extending into the upper chamber 38 of the distributing head 34.

Pressure to the runner servomotor 29 is controlled by a pilot valve 39 which is governed by a pilot valve operating mechanism which includes an extension 41 from the piston 17 of the gate operating servomotor 18 to which extension is fastened a rod 42. The rod 42 is connected with one arm of a pivotally mounted bell crank 43 having a crank 44 fixedly mounted on the spindle of the bell crank. A rod 46 is connected with the crank 44 and, through a crank 47, rotates a shaft 48 on which is mounted a cam 49. The cam 49 engages a roller 51 adjustably mounted on a lever 52 which is pivotally mounted at one end at fixed point 53 and is downwardly biased at the other end by a spring 54 connecting the end of the lever with a fixed point in the control system. The lever 52 is connected by a link 56 with one end of a floating lever 57 to which is connected the stem of the pilot valve 39. Movement of the gate servomotor piston 17 transmits movement through leverage 41, 42, 43, 44 and 46 to the shaft 48 and the cam 49 from which movement is transmitted through the second leverage including elements 51, 52, 56 and 57 by which the pilot valve 39 is moved to admit fluid pressure from a pipe 58 through pipes 59 or 61 into the pressure head 34 and from which pressure head fluid is discharged through the pipes 59 or 61 through a discharge pipe 62. The cam 49 provides means for readily producing a topographical surface by which a definite relation may be obtained between the setting of the gate 13 and the positioning of the runner vanes 22. The cam is preferably made of laminated material to facilitate formation of the proper topographical surface thereof after tests have been made with the entire unit in operation in its final setting. The cam 49 is splined on the shaft 48 to permit movement along the axis thereof and its position may be adjusted by a fork 63 engaging the cam 49 and mounted on a screw 64 rotatable by a hand wheel 66 to change the position of the cam and hence to vary the contour lines of the topographical surface of the cam which may come in contact with the roller 51. The position of the cam 49 is indicated by a suitable gear toothed connection between the hand wheel 66 and a rotatably mounted disk 67 marked with suitable subdivisions and provided with a non-rotatable pointer 68.

When the gate opening is small and the runner vanes are in a comparatively flat position, the starting torque of an adjustable propeller type turbine is very low. A relatively long period of time is therefore required to bring the turbine up to the speed at which the unit may be connected to the transmission line. Further, with the runner vanes in a relatively flat position, the gate must be opened a relatively large amount to overcome the starting friction of the prime mover unit. It is then necessary to move the gate quickly in a closing direction to prevent overspeeding of the turbine after rotation has begun. Means are therefore provided by which the runner vanes may automatically be initially set in a comparatively steep position and then returned to the desired operating angle. Such means include an arm 71 loosely mounted on the cam shaft 48 in such position as to permit engagement of a roller 72 mounted on the arm, with the lever 52 to thereby operate the valve 39.

The position of the arm 71 is determined by adjustable arms 73 and 74 which are mounted to rotate with the cam shaft 48.

Means must also be provided by which the pilot valve 39 is restored to the neutral or mid-position after each operation of the valve in either direction. The restoring movement is derived from the inner shaft tube 33 which moves with the runner vane servomotor piston 28. The upper end of the tube 33 is connected through rod 76, bell crank 77, link 78, bell crank 79 and link 81 with one end of the floating lever 57 to which the stem of valve 39 is connected. The bell crank 79 is provided with a suitable gear toothed connection with a rotatable indicating dial 82 cooperating with a suitable pointer 83 to indicate the angular displacement of the runner vanes. The arc of the dial 82, between the runner vane flat position and the runner vane steepest angular position, is divided into ten equal divisions to provide readings in tenths, which is customary when referring to runner vane positions.

To start the turbine, the arm 71 and roller 72 mounted thereon, are manually brought into vertical position thereby lifting lever 52 which moves the stem of pilot valve 39 upwardly and admits fluid pressure to the underside of the servomotor piston 28 thereby tilting the runner vanes 22 into a steep angular position. As the gates open, the arm 71 is automatically rotated in a counterclockwise direction, due to gate opening action on rod 46, until the arm 71 is forced out of engagement with lever 52 thus permitting the roller 51 to engage the cam 49 which then maintains a predetermined relation between the degree of gate opening and the runner vane setting. Whenever the gates are moved toward the closing position, the arm 73 and the arm 71 are rotated in a clockwise direction which results in lifting of the lever 52. The runner vanes are therefore again set in a steep angular position which permits the turbine to be again started under the most favorable conditions.

The interconnection of large power generating systems in which momentary load fluctuations are relatively small and occur over a relatively large period of time, as compared with the total load, necessitates governing means of extreme sensitivity capable of instant response to the slightest speed variations to maintain adequate distribution system stability and the proper frequency regulation in the distribution system. Such means are herein shown as comprising a unit including an electric motor connected with and therefore responsive to the frequency (or speed), variations of the prime mover generator unit. The electric motor drives a set of flyballs controlling a servomotor for imparting motion to a floating lever controlling a pilot valve which regulates the flow of fluid pressure to the gate operating servomotor 18. The flyball head herein illustrated is already known and will therefore be described only sufficiently to allow comprehension of its functional cooperation with other portions of the control system herein disclosed. The motor 86 is mounted on a housing 87 and drives a set of flyballs 88 arranged within the housing. As is known, the position of the flyballs 88 varies dependent on the motor speed and such variation of position provides movement of a control valve regulating the admission of fluid pressure to and the discharge of fluid pressure from a servomotor, the servomotor and its control valve being only generally shown and

designated 89. The pressure supply pipe and the pressure discharge pipe for the servomotor 89 are indicated at 91 and 92. The flyball servomotor acts on a floating lever 93 pivotally connected with a main lever 94. One end of the main lever 94 is pivotally connected with a collar 96 which is resiliently mounted by a spring 97 abutting against a nut 98 on the stem of a pilot valve 99 for regulating the flow of fluid pressure and from the gate operating servomotor 18. Pressure is applied to the valve 99 from a suitable source through the pipe 58 and is discharged from the valve through the pipe 102. The pipe connections between the valve and the opposite sides of the servomotor piston 17 are designated by 103 and 104. Any change in the conditions of the line which results in a change of the speed of the motor 86 is immediately translated into movement of the flyballs 88 which act on the servomotor 89 and hence on the levers 93 and 94 to move pilot valve 99. The gate operating servomotor 18 therefore immediately commences to vary the opening of the gate 13 to correct the flow of fluid to the prime mover 10 dependent on the degree and the sense of the speed change.

Movement of the gate servomotor 18 must, however, be interrupted before the effect of decreasing or increasing speed of the prime mover 10 would be apparent in the distribution line and hence would produce change in speed of motor 86, to thereby prevent successive over or under regulation or so-called "hunting" of the unit. Valve 99 must therefore be returned to its neutral or midposition with a time delay after the initial operation thereof. Such compensating or restoring means includes the servomotor piston rod extension 41 and the rod 42 connected with one arm of the bell crank 43. The other arm of the bell crank 43 is connected with a rod 106 connected with one end of a lever 107, the other end of which is connected with a pivot 108 on which are mounted a bell crank 109 and a crank 111. Intermediate the ends of lever 107 is connected one piston 112 of a dashpot 113 having a second piston 114 connected with one end of the main lever 94. The dashpot 113 also includes adjustable valves 116 and 117, spring biased in closed direction, which open automatically upon movement of the pistons 112 and 114 and which, when the spring bias is overcome, allow flow of pressure from one chamber to the other of the dashpot and an adjustable needle valve 118 which allows a predetermined quantity of fluid flow between the chambers of the dashpot. The action of lever 94 is stabilized by a spring 119 mounted between the dashpot piston 114 and a boss on the cover of the dashpot and by a spring 121 mounted between the cover of the dashpot and a portion of a synchronizing means.

The synchronizing means is well known in the art and will therefore be only briefly described. Such synchronizer is, however, necessary to a complete control system and is accordingly included herein to permit a complete description of the operation of the system. The synchronizer includes a nut 122 bearing a gear or gear teeth and engaging with the thread of the screw threaded rod of the dashpot piston 114. The nut 122 adjusts the degree of compression of spring 121 and accordingly determines the action and position of the piston 114. The gear teeth of nut 122 engage with an elongated gear 123 rotatably mounted to be driven by gears 124 operable either

manually or remotely by hand wheel or motor 126.

If the flyball head, due to a decrease in the prime mover speed, lowers the floating lever 94, 5 the main lever 94 and the collar 96 are lowered to depress the piston of valve 99 which results in movement of the servomotor piston 17 toward the right to open the gate 13.

The motion of the servomotor piston 17 moves 10 leverage 41, 42, 43, 106 and 107 and forces the dashpot piston 112 upwardly which produces a partial vacuum and pulls the piston 114 down against the action of the compression spring 121. The valve 117 is opened until the spring 121 15 restores the dashpot piston 114 to its balanced or midposition. The downward movement of the piston 114 lowers the right hand end of lever 94 and causes the opposite lever end together with the collar 96 to rise to a higher position which 20 restores the pilot valve 99 to the neutral position. If the load change is small or gradual, the movement of the piston 112 will be correspondingly slow and may not cause movement of the dashpot piston 114 because the needle valve 118 25 permits flow of small quantities of fluid from one chamber of the dashpot to the other chamber thereof. However, if the load change is sudden or large, a sudden or large displacement of the piston 112 occurs and the bypass valve 117 30 is opened to pass fluid between the dashpot chambers which valve 117 thus controls the rate of return to the balanced position of the piston 114. When the displacement of the piston 114 35 is comparatively large, the leverage and the pilot valve 99 are quickly returned to the midposition. The flyballs in the meantime have adjusted themselves to the new load condition and lever 93 has been returned to the normal governor operating position. A speed increase reverses the 40 above action which causes compression under the dashpot pistons 112 and 114. Valve 116 is then opened to bypass fluid and the flow through the needle valve 118 is reversed.

Even if the restoring means for the gate servomotor valve were absolutely perfectly designed 45 and manufactured, a governing system provided with such perfect means would only tend to keep the speed of the governed unit constant regardless of the load thereon. Due to the inherent 50 qualities of different units; at the same speeds, some units will tend to take all of the load and others will tend to run without load. When a plurality of machines of different characteristics are supplying power to the same distribution 55 line, it is necessary that the speed of the machines be allowed to droop an adjustable predetermined amount at various loads to maintain stable operation of the machines. The control system is therefore provided with means for 60 limiting or varying the effect of the restoring mechanism above described. Such limiting means comprise one arm of the bell crank 109 which is connected with a rod 131 which is in turn connected with a bell crank 132 having one arm thereof slotted. The slotted arm of the bell crank 132 is connected by a rod 133 with one end of the lever 93. Upon the occurrence of a 65 change, in the distribution line which causes movement of the control system, the restoring limit device shifts the position of levers 93 and 94 and tends to keep the valve 99 open or closed for an adjustably greater length of time than would otherwise occur thus allowing the unit 70 speed to vary by a predetermined amount neces-

sary to keep the unit under a predetermined load at the given speed.

Shown immediately adjacent the restoring limit device is a device for indicating the position of the vanes comprising the gate 13. Such indicating device includes a rack 136 mounted on the arm 111 and held by a spring 137 in engagement with a gear on the pivot of a pointer 138 operating over a dial 139. Operation of the gate servomotor and of the leverage of the valve restoring means connected with the servomotor actuates the arm 111 and rotates the pointer 138 over the dial to give a constant indication of the gate position.

The conditions of the load supplied or of the 15 distribution system itself or the characteristics of the unit being governed frequently require that the rate at which the unit is governed, that is, the rate at which operating fluid is admitted to the prime mover is made variable to meet the 20 conditions existing. In the case of an adjustable runner vane turbine as herein disclosed, it is of course necessary that the rate of movement of both the gate and of the runner vane be made variable. Such rate control mechanism includes 25 a crank 141 mounted on the pivot 108 which is rotated by the restoring mechanism. The end of crank 141 is connected with a rod 142 which is connected with the end of a crank 143 mounted on a pivot 144 on which is mounted a plate 145 30 bearing a flange 146 formed with cam surfaces. The cam 146 is engaged between pins on one end of an arm 147 rocking about a pivot 148. The other end of the rocker arm 147 is made forked to engage a collar 149 mounted on the stem of 35 valve 99. Movement of the valve 99 in either the opening or closing directions is thus limited by the engagement of collar 149 with the rocker arm 147 and the engagement of the rocker arm pins with cam 146 which cam is rotated by the movement of the restoring mechanism. Naturally, the contours of cam 146 will be made to secure limitation of the rate of movement, either during or at the end of its stroke, of the valve 99 as desired dependent on the characteristics of the 40 unit or of the distribution line.

It is desirable at times to limit the load or the power output of the turbine or to operate the turbine with the gate so blocked that it cannot be moved beyond predetermined limits. Such 50 load limit device should be adjustable to any desired degree and at any time. The load limit includes a crank 151 mounted to rotate with pivot 144 and connected with a rod 152. The rod 152 is connected with one end of a lever 153 having a 55 swivel nut 154 as its fulcrum which is adjustable manually or remotely by means of the hand wheel or motor 156. The other end of the lever 153 is connected with a rod 157 having a spring joint 158 and the rod 157 is connected with one arm of a three armed bell crank 159. Another arm of the bell crank 159 extends into the path of movement of the collar 96 on the stem of the pilot valve 99. An opening movement of the gate 13 rocks the bell crank lever 158 in a clockwise direction and thereby raises the stem of valve 99 to move the gate towards closing position. At the same time the restoring mechanism will return the valve 99 to midposition and further movement of the gate is stopped. That gate may 60 also be closed regardless of the position of the floating lever 94 and to any desirable extent by rotation of the threaded spindle urging the fulcrum nut 154 to a lower position and resulting in 65 an upward movement of the bell crank 159 which 70 75

- raises the valve 99 through the overtravel spring 158. Movement of the load limit is transmitted to a lever 161 pivotally mounted at 162. The lever 161 has connected with one end thereof, a rack 163 held by a spring 164 in engagement with a gear on the pivot of a pointer 166 moving over a dial 167. The setting and momentary position of the load limit device are thus constantly indicated.
- 5 10 15 20 25 30 35 40 45 50 55 60 65 70 75 80 85 90 95
- 10 Means must be provided to prevent opening of the gate 13 during starting beyond the position corresponding to synchronous speed of the unit, until the flyball or governor head has reached the speed at which it will govern the unit. The third arm of the bell crank 159 is connected with a link 168 adjustably engaging with the slotted end of a link 169 connected with the lever 93 at the point of connection thereof with the piston rod of the flyball servomotor 89.
- 15 20 25 30 35 40 45 50 55 60 65 70 75 80 85 90 95
- 20 Upon starting the unit, the right hand end of the main lever 94 is raised, thereby lowering the pilot valve 99 and opening the turbine gate 13. The flyballs are still at rest and the link 169 is at its lowest position allowing the link 168 to be at its lowest position and engage the notch in a latch block 171. As the gate moves toward open position, the cam plate 146 rotates in a counter-clockwise direction and acts on the bell crank 159 by way of the leverage including members 151, 152, 153, 157 and 158 and raises levers 93 and 94 to restore valve 99 to midposition to stop the movement of the turbine gate at some predetermined opening, such as that required for the turbine to reach synchronous speed. As soon as the flyballs start to rotate and come to nearly synchronous speed, the stop link 168 is lifted out of the path of the latch block 171 and the collar 96 and levers 94 and 93 may drop which permits the gate to be opened to a fuller extent as determined by the flyballs.
- 25 30 35 40 45 50 55 60 65 70 75 80 85 90 95
- 30 The operation of a prime mover generating unit, particularly when such operation is not constantly supervised, requires the provision of means by which the entire unit may be shut down upon the occurrence of abnormal operating conditions of any portion of the unit. Such shutdown mechanism should operate fully automatically not only to close the turbine gate but should also shut off the fluid pressure from the various fluid pressure operated devices of the control system upon the occurrence of such conditions as a hot bearing, the opening of a circuit breaker or the like. Control system operating fluid pressure is supplied to the entire control system through the pipe 172 from the usual source of substantially constant pressure. To perform the first of the above two functions, pressure is taken from the pipe 172 through the pipe 173 to a valve 174 which is operated by a solenoid 176 energizable in the usual manner from the portions of the unit subject to abnormal operation. Valve 174 is connected to the pressure supply pipes 177, 178 and 179 connecting with ball valves 181, 182 and an operating cylinder 183 having its piston under spring pressure. Pressure passing through the ball valve 181 may flow through the pipe 184 to an operating cylinder 186 with its piston under spring pressure opposing the fluid pressure supplied thereto. The piston rod of the cylinder 186 is formed with an adjustable lost motion connection 187 to engage a bell crank 188 having one arm extending into the path of movement of the collar 96 on the stem of the pilot valve 99.
- 35 40 45 50 55 60 65 70 75 80 85 90 95
- 35 The control system is also provided with lock-
- ing means requiring the cooperative action of the above mentioned valves 181, 182 and the cylinder 183 and with a latch comprising a double armed crank 191 engaging the stems serving to open the ball valves 181, 182 and mounted on a pivot 192. The pivot also has mounted thereon a latch 193 connected at one end with the piston of the cylinder 183 and provided at the other end thereof with a roller 194 normally in contact with a roller track 196 and a stop 197, both the roller track and the stop being mounted on the extension 41 from the gate servomotor piston rod. The control system is also provided with a manually operable latch and operating means particularly for the purpose of operating the unit when the automatic governor is to be dismantled for inspection or repair. A cross head 198 is mounted at the connection between the gate servomotor extension 41 and the pushrod 42 of the restoring mechanism. The cross head is formed with a square aperture therethrough to adjustably receive the squared end of a threaded rod 199 running in a stationary nut 201 rotatable by a hand wheel 202 through suitable gearing.
- 40 45 50 55 60 65 70 75 80 85 90 95
- 40 The second of the above mentioned functions of the automatic shutdown device, namely the function of shutting off the supply of fluid pressure to the pressure operated cylinders of the control system, is performed by the solenoid 30 valve 174, ball valves 181 and 182 and latch cylinder 183 in combination with a shutoff valve comprising a valve casing 206 provided with a passageway therethrough which may be closed off by an inclined differential piston 207 housed in a cylinder in the valve casing. The lower end of the cylinder is closed by a cover plate providing a cylinder for a hydraulically operated control valve comprising a differential piston 211 joined by a stem of decreased cross section, with a second piston 212 which controls the drainage from below the piston 207 through a passage 216. A small portion of the seat of the differential piston 211 is subjected to the pressure in pipe 172 through the passage 214 to facilitate opening of the valve 212 whenever the ball valve 182 is open to provide communication between the pipe 172 and the under side of the piston 207 through the passages 214 and 216. The valve 207 is then hydraulically balanced and is moved to closed position by the action of the compression spring 208. Drainage from the valve 211 takes place through the pipe 213, ball valve 182, pipe 178 and solenoid valve 174.
- 45 50 55 60 65 70 75 80 85 90 95
- 45 Briefly stated, the operation of the automatic shutdown and the latch cooperating therewith is as follows. If the turbine is shut down and is to be started, the latch engages stop 197 to hold gates 13 closed, energization of the solenoid 176 opens valve 174 admitting fluid pressure to the interlocking ball check valves 181 and 182 and to the latch operating cylinder 183. Ball check valve 182 is opened and pressure is admitted under the piston 211 to raise the control valve 212 and cause the shutoff piston 207 to admit oil to the valve 99 which is then in the position for gate closing and causes servomotor 18 to tend to close the gate 13 thus relieving the action of the stop 197 against latch 193. After relief of the gate opening tendency on the stop 197, fluid pressure admitted to the latch operating cylinder 183 forces its piston and rod upwardly and moves the pivotally mounted latch arm 193 in a counterclockwise direction to move the latch 193 downwardly away from the stop 75

member 197 carried by the extension 41. The stem of valve 181 now forces the ball check downward and off its seat to admit oil under the piston of the shutdown cylinder 186. The shutdown piston is therefore forced upwardly and rotates the bell crank 188 clockwise to allow the valve 99 to move toward the gate opening position. The gate 13 opens until stopped by the power limit mechanism. As soon as the flyballs 88 come up to speed, the link 168 is drawn out of latch block 171 and the prime mover is then fully under the control of the governing system.

If the circuit of the solenoid 176 should be interrupted by a temperature relay or by any other protective means or by the shutdown switch, the valve 174 will close the pressure supply pipes to the valves 181 and 182 and to the latch cylinder 183 and will open the drain connections. The compression spring of the shutdown cylinder 186 then forces the oil under the piston out through the ball valve 181 to the drain, and raises the bell crank 188 which moves the pilot valve 99 to a position at which the gate servomotor 18 closes the gate 13. During the above operation the piston of the latch operating cylinder 183 is forced downwardly by the compression spring causing clockwise rotation of the latch 195 and lever 193, 194 until the roller 194 engages track 196. The track moves toward the left upon movement of the servomotor toward gate closed position and the roller 194 leaves the track so that the latch cylinder may pull the latch 195 into its latching position. The trip lever 191 is rocked together with the latch 195 in a clockwise direction and opens the ball valve 182 to allow pressure to flow from under the piston 211 of the control valve 212 to the drain through the pipe 213, ball valve 182, pipe 178, and solenoid valve 174. A small portion of the seat of piston 211 is exposed to the pressure in pipe 172 through the passageway 214 and the piston 211 is forced downwardly until the valve 212 closes the drain from below the shutoff valve piston 217. Pressure is now admitted from the fluid pressure supply pipe 172 through the passageway 214 and 216 to the under side of the shutoff valve piston 207 thereby balancing the pressure acting on the valve whereupon the spring 208 closes the valve to prevent flow of fluid pressure to any of the operating cylinders of the system. It will thus be observed that as long as the roller 194 engages the track 196 the shutoff valve 207 remains open until the operation of closing of gate is completed, which is as long as the roller 194 engages the track 196 and that only then can the final latching close the shutoff valve. It will also be noted that the stem of valve 181 moves upwardly thus allowing the ball check to seat and preventing pressure through solenoid valve 174 from entering shutdown cylinder 186 until latch 195 has been released even though the solenoid 176 is energized.

The essential elements of the system are shown in the positions of the normal operation of the prime mover but the sequence of the operations of the system will now be described from starting of the prime mover generating unit from standstill, that is, with the gate in closed and latched position, the runner vanes set for a steep angular position to obtain increased starting torque of the turbine and with the automatic shutoff valve closed; through normal operation of the unit and to the final stopping of the unit.

78 The solenoid 176 is connected with a source

of current supply by a conventional switch not shown. Closure of said switch energizes the solenoid 176 and opens the control valve 174. Fluid pressure from the supply pipe 172 is therefore admitted to the interlocking check valves 181, 182 and to the latch operating cylinder 183. The ball check valve 181 remains closed but the ball check valve 182 is opened and fluid pressure flows under piston 211 of the control valve 212 for the shutoff valve 207. Closure of the valve 212 then enables the pressure in the supply pipe 172 to open the automatic shutoff valve 207 and pipe 172 can then supply the full pressure to the several regulating cylinders in the control system. As stated above, the gate 13 is already closed while the turbine is at rest. However the water pressure acting on the gate has a tendency to open the gate by an amount equal to the lost motion in the gate mechanism which tends to force the stop 197 against the latch 195. To overcome the friction between the stop 197 and latch 195 and to unlatch the gate operating mechanism, the pilot valve 99 is caused to move slightly upwardly so that the servomotor piston takes up the lost motion in the gate closing direction. The necessary movement of the pilot valve 99 is obtained by manually controlled movement of the synchronizer operating means 126 or the load limit operating means 156.

The synchronizer, which may be actuated by the hand wheel or by a remotely controlled motor 126, is now operated to raise the one end of main lever 94 which depresses the collar 96 and the pilot valve 99 connected therewith. The pilot valve is now held open and fluid pressure passes to the left face of the piston 17 of the servomotor 18 to open the gate 13 and set the prime mover into operation. As soon as the servomotor piston 17 moves toward the right, the dashpot 113 is actuated to restore the lever 94 and the collar 96 to the neutral position. The rod 142 produces a counterclockwise rocking movement of the cam plate 146 until the stop block 171 engages the link 168 connected with the bell crank 159 and thereby blocks further opening movement of the pilot valve 99 beyond the opening determined by the setting of the block 171. The rate limit cam 146 engages the pins on rocker arm 147 and limits the rate of opening movement of the pilot valve 99 to prevent the servomotor piston 17 from advancing too rapidly. Adjustments of the synchronizer are repeated until the speed of the flyballs closely approaches the full load normal speed operation of the prime mover. At such approximately normal speed, the governor head assumes the automatic control of the prime mover by raising or lowering lever 93 as may be required to secure synchronous operation of the unit. The fulcrum point of the floating lever 94 is then at the point of connection thereof with the dashpot 113. As soon as the flyballs closely approach a normal speed, the link 168 is pulled away from the latch block 171 thereby permitting the rate limit device to function over its entire range.

To obtain the maximum starting torque, the runner vanes are set for a steep angular position, that is, arm 71 and roller 72 are brought into a vertical position. The lever 52 and roller 51 are then raised to necessary steep position and hold the pilot valve 39 in position to admit pressure to the lower face of piston 28 which operates rod 27 and cross head 26 to rotate the runner vanes 22 into the steep angular position necessary to start the runner rotating. As

the gate operating servomotor piston 17 moves toward the right which is the gate opening position, the servomotor motion is transmitted through the extension 41, rod 42 and crank 43 to rod 46 which rotates cam shaft 48 to move the stop 74 in a counterclockwise direction until it pushes the roller 72 out of engagement with the lever 52 thus allowing the roller 51 to again engage the cam 49. The cam thereafter determines the position of valve 39 thus securing positioning of the runner vanes in a predetermined relation to the gate opening to secure the most favorable operating conditions for the turbine.

During normal operation of the unit, load and frequency changes in the distribution line immediately affect the speed of the motor 86 and the position of flyballs 88. The servomotor 89 accordingly shifts the lever 93 which raises or lowers the gate pilot valve 99 to operate the gate servomotor 18. Movement of the gate servomotor actuates the restoring leverage 41, 42, 43, 106, 107 and the dashpot 113 which shifts lever 94 and returns the pilot valve 99 to neutral position to interrupt the gate movement. Movement of the cam 49 from the restoring leverage provides for movement of the runner pilot valve 39 to control the runner servomotor 29 and the leverage 76-81 restoring the runner valve to neutral position. Minor speed variations are controlled exclusively by the flyball head without action of the dashpot due to the regulated flow of fluid from one dashpot chamber to the other through the needle valve 118. Larger speed changes bring into play the internal action of the dashpot which thus attempts to limit quick movement of the gate servomotor to a short interval of time. Large and quick flyball and dashpot movements are, however, spread over a relatively long period of time by the operation of the rate limiting cam 146 and its rocker arm 147 acting on the stem of pilot valve 99. The power output or load limit performs its well known function of preventing opening of the gate beyond a predetermined point to limit the power obtainable from any one unit provided with such power limiting means. The safety connection between the load or power limit device and the flyball head acts to prevent full opening of the gate during starting operation and thus automatically limits the unit speed during starting or if the flyballs are not operating.

The operation of the unit is normally interrupted either by operation of the synchronizer 122-126 in the reverse direction from that above mentioned for starting at which time the synchronizer will pull down the lever 94 and will raise the valve 99 to cause a closing of gate 13; or the load limit device 151-159 may be operated by turning either the hand wheel or by operating the motor 156 in a direction to lower the nut 154 which lowers lever 153 and raises the arm of bell crank 159, to press against the collar 96 and thus to raise the stem of the valve 99 to close the gate 13. Another method of stopping the unit is to deenergize solenoid 176 which then operates the automatic shutdown device as above described. Emergency operation of the shutdown device has already been previously described and accordingly is not repeated.

Consideration of the above disclosure will show that the control system herein set forth provides for the control of a prime mover having a gate controlling the flow of operating fluid to the prime mover and in which the gate is operated by a fluid pressure operated servomotor. The gate servomotor is controlled by a speed respon-

sive means herein called a flyball or governor head and provided with a servomotor operating a pilot valve controlling the pressure flow to the gate operating servomotor. Means comprising a leverage and a dashpot are connected between the gate operating servomotor and the flyball head to restore the pilot valve to its neutral position. In addition to the above elements essential in any control system, the present system is provided with means for controlling or limiting the rate of gate operation which means include the cam plate and rocker arm connected with the restoring mechanism and with the gate pilot valve. Means are also provided for limiting the power output of the prime mover both during normal operation of the control system and particularly when the prime mover is being started, that is, when the flyballs are ineffective, and includes an adjustable leverage operated from the restoring mechanism on the gate pilot valve and another adjustable leverage connecting the first mentioned leverage with the flyball head. A speed droop control device connects the levers actuated by the flyball head with the restoring mechanism to keep the prime mover operating within its most stable range regardless of the power output which may be required therefrom. Shutdown and shutoff means are provided to stop the prime mover upon the occurrence of abnormal conditions and also to render the control system ineffective. The several valves and power operating cylinders cooperating to form shutdown and shutoff devices may be operated either in response to abnormal condition or voluntarily as may be desired.

When the prime mover is a turbine with adjustable runner vanes as herein disclosed, in addition to the above elements which were stated to be essential to any control system, it is necessary that a servomotor be provided to adjust such vanes and, when a fluid pressure operated servomotor is used, a pilot valve is required. A definite relation must be maintained between the gate and the runner vane settings and such relation is obtained by a leverage actuated by a cam which is rocked by a connection with the gate operating servomotor. Such adjustable runner machine should be provided with means to initially set the runner vanes at a steep angle to improve the prime mover starting characteristics and such means are provided in an arm acting on the pilot valve actuating leverage and with operating and limiting stops also operated from the gate servomotor.

Although but one embodiment of the present invention has been illustrated and described herein, it will be apparent to those skilled in the art that various changes and modifications may be made therein without departing from the spirit of the invention or from the scope of the appended claims.

It is claimed and desired to secure by Letters Patent:

1. In a control system for a prime mover having a gate controlling the flow of operating fluid thereto, means for operating the gate, means responsive to the speed of the prime mover for controlling said gate operating means, means for restoring said gate operating means to midposition, and means actuated by said restoring means for controlling the rate of movement of said gate operating means.

2. In a control system for a prime mover having a gate controlling the flow of operating fluid thereto, means for operating the gate, means re-

sponsive to the speed of the prime mover for controlling said gate operating means, means for restoring said gate operating means to midposition, a cam plate actuated by said restoring means, and a rocker arm engaging said gate operating means and the cam surface of said plate for controlling the rate of movement of said gate operating means.

3. In a control system for a prime mover having a gate controlling the flow of operating fluid thereto, a servomotor for operating said gate, a flyball governor responsive to the speed of the prime mover for controlling the operation of said servomotor, a leverage connected with said servomotor, a dashpot connecting said governor with said leverage, said leverage and said dashpot cooperating to restore said servomotor to the midposition thereof, a cam plate actuated by said restoring means, and a rocker arm engaging said gate operating means and the cam surface of said plate for controlling the rate of movement of said gate operating means.

4. In a control system for a prime mover having a gate controlling the flow of operating fluid thereto, means for operating the gate, means responsive to the speed of the prime mover for controlling said gate operating means, means for restoring said gate operating means to midposition, and means for limiting the degree of action of said restoring means on said gate operating means to control the speed droop of the prime mover.

5. In a control system for a prime mover having a gate controlling the flow of operating fluid thereto, means for operating the gate, means responsive to the speed of the prime mover for controlling said gate operating means, means for restoring said gate operating means to midposition, and an adjustable leverage connecting said gate operating means with said restoring means for limiting the action of said restoring means on said gate operating means to control the speed droop of the prime mover.

6. In a control system for a prime mover having a gate controlling the flow of operating fluid thereto, a servomotor for operating said gate, a flyball governor responsive to the speed of the prime mover for controlling the operation of said servomotor, a leverage connected with said servomotor, a dashpot connecting said governor with said leverage, said leverage and said dashpot cooperating to restore said servomotor to the midposition thereof, a cam plate actuated by said restoring means, a rocker arm engaging said gate operating means and the cam surface of said plate for controlling the rate of movement of said gate operating means, and an adjustable leverage connecting said gate operating means with said restoring means for limiting the action of said restoring means on said gate operating means.

7. In a control system for a prime mover having a gate controlling the flow of operating fluid thereto, means for operating the gate, means responsive to the speed of the prime mover for controlling said gate operating means, means for restoring said gate operating means to the midposition thereof, and an adjustable leverage connecting said gate operating means with said gate restoring means for limiting the power output of the prime mover during operation thereof.

8. In a control system for a prime mover having a gate controlling the flow of operating fluid thereto, means for operating the gate, means re-

sponsive to the speed of the prime mover for controlling said gate operating means, means for restoring said gate operating means to the midposition thereof, means for limiting the power output of the prime mover during operation thereof, and means for eliminating the action of said power limiting means during starting of the prime mover.

9. In a control system for a prime mover having a gate controlling the flow of operating fluid thereto, means for operating the gate, means responsive to the speed of the prime mover for controlling said gate operating means, means for restoring said gate operating means to the mid position thereof, means for limiting the power output of the prime mover during operation thereof, and an adjustable leverage connecting said speed responsive means with said power limiting means for eliminating the effect of the latter during starting of the prime mover.

10. In a control system for a prime mover having a gate controlling the flow of operating fluid thereto, means for operating the gate, means responsive to the speed of the prime mover for controlling said gate operating means, means for restoring said gate operating means to the mid position thereof, a source of fluid pressure, a cylinder having a piston engageable with said gate operating means, and valves controlling pressure flow to and from said cylinder upon the occurrence of predetermined conditions of operation of the prime mover to supersede all other means in controlling operation thereof.

11. In a control system for a prime mover having a gate controlling the flow of operating fluid thereto, means for operating the gate, means responsive to the speed of the prime mover for controlling said gate operating means, means for restoring said gate operating means to the mid position thereof, means for automatically interrupting operation of the prime mover upon the occurrence of predetermined conditions thereof, and means controlled by said interrupting means for interrupting the supply of energy to the entire control system.

12. In a control system for a prime mover having a gate controlling the flow of operating fluid thereto, means for operating the gate, means responsive to the speed of the prime mover for controlling said gate operating means, means for restoring said gate operating means to the mid position thereof, a source of fluid pressure, a cylinder having a piston engageable with said gate operating means, valves controlling pressure flow to and from said cylinder upon the occurrence of predetermined conditions of operation of the prime mover to supersede all other means in controlling operation thereof, and a latch cooperating with said valves to control the pressure flow to said cylinder.

13. In a control system for a prime mover having a gate controlling the flow of operating fluid thereto, means for operating the gate, means responsive to the speed of the prime mover for controlling said gate operating means, means for restoring said gate operating means to the mid position thereof, means for automatically interrupting operation of the prime mover upon the occurrence of predetermined conditions thereof, and a valve controlled by said interrupting means for rendering the entire control system ineffective upon operation of said valve.

14. In a control system for a prime mover having a gate controlling the flow of operating fluid thereto and having a runner with

adjustable vanes, means for operating said gate responsive to the speed of the prime mover, means for adjusting the position of said runner vanes responsive to the operation of said gate operating means, and means operable by said vane adjusting means for setting the runner vanes at a steep angle prior to starting of the prime mover.

15. In a control system for a prime mover having a gate controlling the flow of operating fluid thereto and having a runner with adjustable vanes, means for operating said gate responsive to the speed of the prime mover, a servomotor for adjusting the position of the runner vanes, means controlled by said gate operating means for controlling the operation of said servomotor, and means operable by said gate operating means to adjust said servomotor controlling means to set the runner vanes at a steep angle prior to starting of the prime mover.

16. In a control system for a prime mover having a gate controlling the flow of operating fluid thereto and having a runner with adjustable vanes, means for operating said gate responsive to the speed of the prime mover, a servomotor for adjusting the position of the runner vanes, means for controlling the operation of said servomotor, a leverage controlled by said gate operating means for operating said servomotor controlling means, and an arm operated by said gate operating means and acting on said leverage to adjust the same to set the runner vanes at a steep angle prior to starting of the prime mover.

17. In a control system for a prime mover having a gate controlling the flow of operating fluid thereto and having a runner with adjustable vanes, means for operating said gate responsive to the speed of the prime mover, a fluid pressure operated servomotor for adjusting the position of the runner vanes, a valve controlling the flow of fluid pressure to and from said servomotor, a leverage controlled by said gate operating means for controlling movement of said valve, an arm movable into engagement with said leverage to cause movement thereof to set the runner vanes at a steep angle prior to starting of the prime mover, and means operable by said gate operating means to move and to limit the movement of said arm.

50 18. In a control system for a prime mover having a gate controlling the flow of operating fluid thereto, means for operating the gate, means responsive to the speed of the prime mover for controlling said gate operating means, means for restoring said gate operating means to mid position, a leverage connected with said restoring means, a plate having a cam surface and being mounted for oscillation by said leverage, and a pivotally mounted rocker arm engaging said gate operating means and the cam surface of said plate for controlling the rate of movement of said gate operating means.

19. In a control system for a prime mover having a gate controlling the flow of operating fluid thereto, means for operating the gate, means responsive to the speed of the prime mover for controlling the said gate operating means, means for restoring said gate operating means to the midposition thereof, a cylinder having a piston engageable with said gate operating means, a valve interrupting the flow of pressure to said cylinder upon the occurrence of abnormal conditions in the operation of the prime mover, and 75 a valve allowing discharge of fluid under pressure

from said cylinder upon operation of the first said valve.

20. In a control system for a prime mover having a gate controlling the flow of operating fluid thereto, means for operating the gate, means responsive to the speed of the prime mover for controlling the said gate operating means, means for restoring said gate operating means to the mid position thereof, a cylinder having a piston engageable with said gate operating means to cause movement thereof in gate closing direction and compressing a spring upon the admission of fluid pressure thereto, a solenoid valve closed upon the occurrence of abnormal operation of the prime mover, and a valve opened by expansion of the spring in said cylinder upon closing of said solenoid valve, said valves respectively controlling the admission to and the discharge of fluid pressure from said cylinder.

21. In a control system for a prime mover having a gate controlling the flow of operating fluid thereto, means for operating the gate, means responsive to the speed of the prime mover for controlling said gate operating means, means for restoring said gate operating means to the mid position thereof, means for automatically interrupting operation of the prime mover upon the occurrence of predetermined conditions thereof, a latch engageable with said gate operating means, and pressure operated means for actuating said latch.

22. In a control system for a prime mover having a gate controlling the flow of operating fluid thereto, means for operating the gate, means responsive to the speed of the prime mover for controlling said gate operating means, means for restoring said gate operating means to the mid position thereof, means for automatically interrupting operation of the prime mover upon the occurrence of predetermined conditions thereof, a latch engageable with said gate operating means, a fluid pressure servomotor for actuating said latch, and a valve operated responsive to abnormal operation of the prime mover for interrupting supply of pressure to said servomotor.

23. In a control system for a prime mover having a gate controlling the flow of operating fluid thereto, a fluid pressure operated servomotor for operating the gate, a fluid pressure operated valve for controlling the supply of pressure to said servomotor, and a plurality of separate valves operable responsive to different conditions to cause a closing of said pressure operated valve upon the occurrence of abnormal operation of the prime mover.

24. In a control system for a prime mover having a gate controlling the flow of operating fluid thereto, means for operating the gate, means responsive to the speed of the prime mover for controlling said gate operating means, means for restoring said gate operating means to the mid-position thereof, a leverage connecting said speed responsive means and said gate restoring means for limiting the power output of the prime mover during operation thereof, an adjustable leverage connecting said speed responsive means with said power limiting leverage, and a stop actuated by said restoring means to limit the movement of said adjustable leverage in one direction to thereby eliminate the effect of said power limiting leverage during starting of the prime mover.

25. In a fluid pressure operated control system for a prime mover having a gate controlling the flow of operating fluid thereto, means for operat-

75

- ing the gate, means responsive to the speed of the prime mover for controlling said gate operating means, means for restoring said gate operating means to the mid-position thereof, valve means 5 for interrupting the operation of the prime mover, valve means for shutting off the flow of fluid pressure to the entire control system, and automatic means responsive to the occurrence of predetermined abnormal conditions to cause operation 10 of both said interrupting means and said shut off means.
26. In a fluid pressure operated control system for a prime mover having a gate controlling the flow of operating fluid thereto, means for operating the gate, means responsive to the speed of the prime mover for controlling said gate operating means, means for restoring said gate operating means to the mid-position thereof, valve means for interrupting the operation of the prime 15 mover, a fluid pressure operated valve for shutting off the flow of fluid pressure to the entire control system, and a plurality of valves automatically

responsive to the occurrence of predetermined abnormal conditions to cause operation of both said interrupting means and of said shut off valve.

27. In a fluid pressure operated control system 5 for a prime mover having a gate controlling the flow of operating fluid thereto, means for operating the gate, means responsive to the speed of the prime mover for controlling said gate operating means, means for restoring said gate operating 10 means to the mid-position thereof, a fluid pressure operated valve for shutting off the flow of fluid pressure to the entire control system, a valve automatically responsive to predetermined abnormal conditions to cause operation thereof, and a plurality of valves controlled by said automatic valve, all of said valves cooperating to cause operation of both said interrupting means and said shut off valve.

JOSEPH J. RINC. 20
BEVERLY R. NICHOLS.
